UNITED STATES PATENT OFFICE.

ANDREW H. CALDWELL, OF PORT BYRON, NEW YORK.

PIPE-CLAMP.

1,142,235.

Specification of Letters Patent.

Patented June 8, 1915.

Application filed July 11, 1913. Serial No. 778,526.

To all whom it may concern:

Be it known that I, ANDREW H. CALDWELL, a citizen of the United States, and a resident of Port Byron, in the county of 5 Cayuga and State of New York, have invented a certain new and useful Pipe-Clamp, of which the following is a specification.

This invention relates to pipe clamps for 10 holding finished or plated pipes in pipe vises without marring the pipe while the same is being operated on or threaded, and has for its object a clamp capable of holding a plurality of pipes of different sizes, 15 which clamp is particularly simple in construction, economical in manufacture and highly efficient in use; and the invention consists in the combinations and constructions hereinafter set forth and claimed.

20 In describing this invention reference is had to the accompanying drawings in which like characters designate corresponding parts in all the views.

Figure 1 is an elevation of my pipe clamp 25 with a pipe therein. Fig. 2 is a plan of the pipe clamp, the jaws being open. Fig. 3 is a transverse section through the clamp with the jaws closed, a pipe being shown therein.

This pipe clamp comprises a main jaw 30 having concave working faces of different radii, and a plurality of jaws each having a working face complementary to one of the working faces of the main jaw.

The working faces of the main jaw are 35 in the form of cylindrically concave channels arranged end to end and with their axes at an obtuse angle to each other so that when the pipe is held in the working face of larger radii it can pass beyond the working face of less radii, as seen in Fig. 1.

1 is the main jaw which consists of sections 2, 3 rigidly secured together and usually formed integral, the sections being arranged at an obtuse angle to each other.

45 4 and 5 are the cylindrically concave channels in the faces of the jaws, these channels being of different radii and running into each other at their contiguous ends and the axes of such channels being arranged at an 50 obtuse angle to each other so that the channel of smaller diameter is thrown out of the way of the pipe in the channel of larger diameter.

6 and 7 are the jaws having channels 8

and 9 complementary to the channels 4 and 5 respectively. The jaws 6 and 7 being hinged at 10 to the main jaw. The channels are faced with a suitable material 11 designed to engage the pipe and prevent marring thereof, and the margins of such material 12 lap over onto ledges 12 formed in the edges of the jaws.

The channels 4, 5 and 8, 9 are designed to hold pipes of different diameter, as for instance, $\frac{3}{8}$ " pipe and $\frac{1}{2}$ " pipe and owing to 65 the fact that the sections of the main jaw are arranged at an angle to each other the $\frac{1}{2}$ " pipe, when held in position can project beyond the section of the main jaw having $\frac{3}{8}$ " working faces.

The clamp is usually made to hold two pipes, and the channels are made to fit two sizes of pipe which are usually used together on certain classes of work, as for instance basin and bath supply pipes are in 75 two sizes $\frac{3}{8}$ " and $\frac{1}{2}$ " and one form of my pipe clamp is applicable to these sizes of pipes. Hence a plumber, when going out on a job can select the pipe clamp he will need and will not have to carry a number 80 of such pipe clamps.

What I claim is:

1. A pipe clamp including a main jaw formed with an angle therein between its ends, the working faces thereof on opposite 85 sides of the angle being of different radii, and movable jaws coacting with the portions of the main jaw on opposite sides of its angle, substantially as and for the purpose described.

2. A pipe clamp comprising a main jaw having concave working faces of different radii for fitting different sizes of pipes, the working faces being arranged with their axes at an obtuse angle to each other, and 95 jaws for coacting with the main jaw, each of the latter jaws having a working face complementary to one of the working faces of the main jaw, substantially as and for the purpose specified.

3. A pipe clamp comprising a main jaw including sections rigidly connected together and arranged end to end at an obtuse angle, the sections being formed with lengthwise channels opening into each other, the 105 channels being concave and of different radii and arranged with their axes at an obtuse angle to each other, and a jaw for

each section of the main jaw, each of the latter jaws having a channel complementary to one of the channels of the main jaw, substantially as and for the purpose set forth.

5 In testimony whereof, I have hereunto signed my name in the presence of two attesting witnesses, at Clayton, in the county

of Jefferson, in the State of New York, this 10th day of June, 1913.

ANDREW H. CALDWELL.
